UNITED STATES PATENT OFFICE.

EDWARD G. WORLEY, OF NEW YORK, N. Y.

DESIGN FOR AN ELECTRIC-BELL CASE.

SPECIFICATION forming part of Design No. 25,842, dated July 28, 1896.

Application filed May 2, 1896. Serial No. 590,034. Term of patent 14 years.

To all whom it may concern:

Be it known that I, EDWARD G. WORLEY, a citizen of the United States, residing at New York, (Kingsbridge,) in the county of New York and State of New York, have invented and produced a new and original Design for Electric-Bell Cases, of which the following is a specification, reference being had to the accompanying drawings, forming a part thereof.

10 In the drawings forming part of this specification, Figure 1 is a front view of an electric-bell casing, showing my new and original design; and Fig. 2, a side view thereof.

The leading feature of my new and original 15 design consists of a circular body portion or head A, having at one side an oblong extension B, which is rectangular in form, being provided with parallel sides b and a transverse end piece b^2 , and the circular body portion or head A is provided with a convex cap

or cover D on one side thereof, and said oblong extension is provided with a flat cap or cover d on the same side, and the exposed surfaces of my new and original design for an electric-bell casing are all smooth.

25 My design is symmetrical in form and well adapted to serve as an ornament, as well as for a casing for electric bells, and

Having fully described the same, I claim as new and desire to secure by Letters Patent— 30 The design for electrical-bell cases as herein shown and described.

In testimony that I claim the foregoing as my invention I have signed my name, in presence of the subscribing witnesses, this 28th 35 day of April, 1896.

EDWARD G. WORLEY.
